INVENTOR,
R. H. Richardson.

BY
Sterling P. Buck,
ATTORNEY.

UNITED STATES PATENT OFFICE.

ROBERT H. RICHARDSON, OF RICHMOND, VIRGINIA.

SCALP SYRINGE.

Application filed October 20, 1927. Serial No. 227,520.

This invention relates to scalp syringes, and is an improvement on my invention which is described and claimed in Patent Number 1,540,863.

5 The main object of this invention is to provide an exceedingly convenient and effective scalp syringe which includes a container having rigid sides and a flexible end which may properly be designated a spring-bottom, such 10 bottom being depressible for forcing limited quantities of hair-tonic or other liquid through the tubular applicator teeth, and the spring action of said bottom returning it to its normal downwardly convexed or bulged 15 relation.

Another object is to provide a device of this character with a screen between the mouth of the container and the outlets of the applicator teeth, to specially adapt this device to 20 use with various fluids, for instance, light or thin fluids such as hair tonics, and relatively heavy or thick fluids, such as shampoo liquids.

Other objects and important features are 25 pointed out or implied in the following details of description, in connection with the accompanying drawings in which:

Figure 1 is a side view showing the container in full elevation, the other parts being 30 in central vertical section.

Figure 2 is a vertical sectional view, the section being indicated by the line 2—2 of Figure 3.

Figure 3 is a view showing the cap or cover 35 in horizontal section along the line 3—3 of Figure 2, the remaining part being in full plan.

Figure 4 is a view showing the device inverted or in the useful position for applying tonic or other liquid material to the scalp of a person, the scalp being indicated by the broken curved line, and the inverted bottom part of the container being shown in central vertical section, also depressed as when a downward pressure is exerted thereon by the hand of the user.

It should be understood that the drawings are exaggerated as to the size of the device, as to the thickness of the wall and bottom of the container, and as to the convexity of such bottom in both the normal relation (Figure 2) and the depressed relation (Figure 4).

Referring to these drawings in detail, in 55 which similar reference characters correspond to similar parts in the several views,

and in which the applicator 5 (of rigid material) and the cap or cover 6 are substantially the same as in my prior patent, above referred to, except as to means of attachment, 60 and includes an outer annular series of solid teeth 7 and an inner group of tubular teeth 8; the invention includes a container 9 of metal or other relatively stiff and springy material, the main body of this container being frusto- 65 conical or tapering from its upper part to its lower part, the taper being considerable so that the lower part is much broader than the upper part, and its bottom 10 is of relatively large area and normally outwardly 70 or downwardly convexed, this bottom 10 being springy and capable of being depressed, as shown at 10^a, Figure 4, and capable of returning to the normally outwardly bulged or convexed relation such as shown (exaggerated) in Figure 2. The bottom 10 is also 75 preferably provided with an annular inwardly bulged or convexed part 10^b which has its outer edge united with the frusto-conical wall 11, and it should be understood that the bottom 10 may either be formed integrally with the wall 11; or may be separately formed, and united therewith by any appropriate means. The wall 11 and periphery of the bottom 10 preferably extend slightly below the level of the center of the bottom 10, 80 so the device will stand level and firm on the top of a dresser, shelf, table or the like. The container is formed with an annular ridge or offset portion 12 under which may extend 85 the thumb and fingers of a hand of the user, thereby providing a firm hand-hold while the palm of the hand presses the part 10^a downward when applying the device in the position shown in Figure 4. The annular 90 ridge 12 also serves as a rest for the normally lower end or margin 13 of the inverted cup 6 which constitutes the cap or cover of the device. The cover cap protects the applicator from injury, dust and germs, and from 95 drying and clogging of liquids in the passages of the feeding teeth, and prevents 100 evaporation of liquids while standing. Attachment of cover cap is simple, having no threaded means. That, manufacturers say, 105 reduces the cost of its manufacture, and is an improvement on the cap in my former 110 syringe patent.

The neck 14 of the container is formed with screw threads or a single turn of screw thread, as indicated at 15, and the applicator 5 is internally threaded so as to removably en-

gage with the screw thread 15, and when the neck or mouth of the container is opened, by removal of the applicator, the container may be filled through the neck or mouth 14.

5 A screen 16 is preferably formed of a number of layers of the finest mesh cloth, the periphery of such screen fitting snugly against the annular inner surface of the applicator 5, so as to be removable and replaceable with 10 such applicator, without danger of being displaced, but being easily removable and replaceable in the socket of the applicator, as directed for use with various fluids and cleaning the screen. This cloth means is a distinct 15 feature of my syringe and an important element that differentiates it from all other known fountain combs or like devices, in that it is for the essential and desirable purpose of controlling and moderating the flow of liquids from the comb. It may be of ordinary cloth or of closely woven metal cloth. The 20 layers of fine mesh cloth or fabric forming the screen are to prevent excessive flow or squirting of the liquid and excessive wetting 25 of the scalp. This means is believed to be new and original. With the screen, my syringe is a scalp moistener, and not a squirter. This screen is not for a filter. My syringe is 30 filled with liquids by unscrewing the applicator and removing the screen from mouth of container. The screen element is to be replaced when using light or thin fluids in syringe, but is not inserted for use with thick or heavy shampoo fluids, unless desired by user. 35 Any appropriate number of the thin cloth layers can be used to furnish the degree of fluid feed or scalp moistening desired.

From the foregoing description, it will be seen that, these improvements are of very considerable importance as to the convenience 40 and effectiveness of the device.

It is not my intention to limit my patent protection to the exact details shown and de-

scribed in the drawings and foregoing description, but changes may be made within the scope of the inventive ideas as implied and claimed.

What I claim as my invention is:

1. A scalp syringe or the like which includes a container having a rigid frusto-conical wall and a springy and compressible bottom, said container also including a neck or mouth portion at the opposite end from said bottom, an applicator including substantially rigid tubular teeth and a socket in immediate communication with one another, said socket being adapted to receive said neck and to engage therewith for securing the applicator on said container, a thin cloth screen fitted in said socket between the mouth of said container and the hollows of the tubular teeth and against the margins of the said hollows, substantially as shown.

2. The structure defined by claim 1, said screen including a plurality of sheets of fine mesh thin cloth having their peripheries fitted against the inner annular surface of said socket and their surfaces clamped between said neck or mouth portion and said applicator and against the margins of the said hollows.

3. The structure defined by claim 1, the said container having an annular offset portion between said neck and said frusto-conical wall for engagement with a thumb and fingers while the palm of the hand presses the compressible bottom, and a cover fitted telescopingly around the container and being limited in its movement by the said offset portion, said cover being removable so the said offset portion is accessible to the thumb and fingers while the said teeth are accessible for contact with the scalp of the user.

In testimony whereof I affix my signature.

ROBERT H. RICHARDSON.
